UNITED STATES PATENT OFFICE.

FRED A. SCHMITZ, OF YOUNGSTOWN, OHIO, ASSIGNOR TO THE GENERAL FIREPROOF-
ING COMPANY, OF YOUNGSTOWN, OHIO, A CORPORATION OF OHIO.

SHIPPING CRATE.

Application filed July 23, 1921. Serial No. 486,968.

To all whom it may concern:

Be it known that I, FRED A. SCHMITZ, a citizen of the United States, residing at Youngstown, in the county of Mahoning 5 and State of Ohio, have invented certain new and useful Improvements in Shipping Crates, of which the following is a specification.

This invention relates to shipping crates, 10 particularly of the class employed in crating furniture.

A primary object of the invention is to provide a crate of this character possessing special utility in the crating and shipping 15 of steel furniture such as filing cabinets, safes, etc. The usual practice in that regard is to build or construct a framing to form a crate about the article to protect it in transit against damage or destruction and 20 also preserve the varnished or enameled surface thereof against scratching or marring in handling. As a rule the parts of the crate are nailed or otherwise fastened about the article to be shipped in such a manner as to 25 meet the individual requirements of each article, and notwithstanding the fact that such crates are braced and reinforced against movement to avoid chafing at points of contact with the article, the high polished or 30 finished surfaces of the article frequently become damaged due to the relative movement between the crate parts and the article.

Accordingly, the present invention aims 35 to obviate as far as possible the liability of damage of the character mentioned to articles in transit, and also in the act of crating by providing a crate structure which may, for the greater part at least, be made up in units apart from the crating operation and 40 then assembled about the article in a quick and convenient manner. In the latter connection it is proposed to rigidly connect certain of the crate units or sections with 45 the article in such a manner as to avoid relative movement therebetween and at the same time provide a thoroughly practical means for assembling the remaining sections to enable the entire structure to withstand the shocks of loading and unloading and 50 also properly distribute the effect of such shocks or blows in a manner that will not in any way injure the article contained within the crate.

With the above and other objects in view 55 which will more readily appear as the na-

ture of the invention is more clearly understood, the same consists in the novel construction, combination, and arrangement of parts hereinafter more fully described, illustrated and claimed. 60

A preferred and practical embodiment of the invention is shown in the accompanying drawings, in which:

Figure 1 is a perspective view of an article crated in accordance with the present invention. 65

Figure 2 is an exploded perspective view of the crate parts.

Figure 3 is an enlarged detailed horizontal sectional view taken on the line 3—3 of 70 Figure 1.

Figure 4 is a horizontal cross sectional view taken on the line 4—4 of Figure 1.

Figure 5 is a vertical sectional view with the intermediate portions of the crate broken 75 away to illustrate the top and bottom construction of the crate.

Similar reference characters designate corresponding parts throughout the several figures of the drawings. 80

One of the distinctive features of the present invention is the provision of previously constructed crate units or sections, certain of which may be bolted or otherwise securely attached to the article so as to become in effect a rigid part thereof and thereby eliminate chafing or rubbing between the unit and the article. The sections thereby become thrust receiving sections for better distributing the forces of compression, shear, 90 and tension to the article. In that way a strong and rigid crate structure is formed that offers substantial resistance to compression and shear forces imposed on the sides of the crate, whereby under ordinary conditions of shipping no movement can occur between the crate parts and the object being shipped. 95

The invention is obviously applicable to all types of articles to be shipped, such as 100 cabinets, desks, tables, machines or other objects but for sake of convenience the present drawings illustrate the adaptation of the invention in the shipping of a filing cabinet designated generally as F. This cabinet includes the usual sliding drawers D and the side walls W, having therein the opening O for receiving the anchoring or fastening bolts for connecting the cabinet with an adjacent cabinet of a battery or stack. These 105 110

openings O, as usual, may be of any desired number and location, but as shown in Figure 2 are preferably located near the corners of the cabinet in order to afford better distribution of the fastening means. When the cabinet is to be crated for shipment the said openings O may be conveniently utilized for receiving a novel fastening unit A (Figure 3) for rigidly coupling the main units or side sections 1 of the crate to the sides of the cabinet.

As will be observed from the drawings the side units 1 are preferably in the form of rectangular frames including the relatively stout frame bars 2-2 and the cross pieces 3, the said frame bars 2-2 preferably being longer than the vertical height of the cabinet and provided at suitable points, corresponding to the spacings of the openings O in the side wall of the cabinet, with openings 3 for registering therewith. When the openings O in the side wall and openings 3 in the bars of the unit 1 register the top ends 2^a of the frame bars have a substantial projection above the plane of the top of the cabinet F and the lower ends 2^b of the bars have a similar projection below the bottom of the cabinet. As the dimensions and specifications of the cabinets are well known in the factory the side units 1 of the crates may be previously constructed in a form ready to be assembled on the side of the cabinet by means of the novel fastening devices A, thus avoiding the use of nails or other fastenings at the time of crating which otherwise might puncture or injure the cabinet in event of being misplaced or piercing beyond the limits of the frame by reason of being too long for the thickness thereof.

The said fastening devices A may be of any suitable and convenient type, but in order to provide a thoroughly practical and effective fastening or coupling, it is preferred to use a suitable bolt 4 adapted to be inserted through the openings O and 3, respectively in the side wall of the cabinet and the frame bars of the side unit, the said bolt having the head thereof bearing against a relatively large cupped washer 5 arranged at the inner side of the wall W while the outer side of the circular boss in which the opening O is formed is also fitted with a cupped ring-like washer 6 whose flanged edge 7 is adapted to have a biting contact with the wooden frame bar 2 as shown in Figure 3.

For the purpose of insuring a tight assembly of the washers on the bolt 4 a loose filler nut 8 may be placed upon the intermediate portion of the shank of the bolt, while the outer threaded portion of the bolt may receive a relatively large washer 9 for the tightening nut 10 to work against.

When the nut 4 is tightened up on the

threaded end of the nut 4 the entire fastening unit will be drawn into operative position and in addition to causing the flanged edge 7 of the washer 6 to bite into the wood, the loose nut 8 will also be embedded therein to further increase the rigidity of the coupling or connection between the frame bar and the wall of the cap.

By reason of the spaced washers 5 and 6 engaging the inner and outer sides of the bars having the opening O it will be apparent that the clamping effect exerted by the bolt will be distributed in a thoroughly practical and efficient manner to the side walls of the cabinet, and thus prevent distortion of the reinforcing rib of the side wall in which the boss is located. When the side unit of the crate structure is thus attached to the side wall of the crate by the several fastening units A it will be apparent that the side units of the crate are in effect a rigid and integral part of the cabinet, and when thus assembled at the sides of the cabinet the same constitute the basis for completing the assembly of the crate.

By reason of the ends 2^a and 2^b of the frame bars of the side unit projecting above and below the top and bottom of the cabinet the top and bottom crate sections 11 and 12 may be readily fitted into place between the projections of the opposite side walls. The said sections 11 and 12 may be previously prepared, and respectively consist of the side members 11^a and cross members 11^b and the side members 12^a as clearly shown in the drawing. In each instance the length of the top and bottom sections is greater than the depth of the cabinet so that the opposite ends 11^c and 12^c respectively project beyond the front and rear walls of the cabinet to compensate for the thickness of the front and back crate sections.

The said front and back sections are designated as 14 and 15 and are of substantially the same length as the vertical height of the cabinet thereby to fit between the projecting ends 11^c and 12^c of the top and bottom sections; and as shown, said sections may be composed of the frame members 14^a and 15^a respectively and suitable cross pieces 14^b and 15^b. In the case of the front section 14 the cross pieces 14^b are preferably of relatively thick cross-section for the purpose of providing the necessary clearance between the body of the section and the front of the cabinet where the drawer pulls of the drawer D are located. As will be seen from Figures 4 and 5 for example, the cross pieces 14^b rest upon the drawer pulls or handles for the drawer and not only protect the same against breakage but at the same time prevent the drawers from moving about during the transportation of the cabinet.

The top, bottom, front and back sections 11, 12, 13 and 14 respectively, are, like the

side units or sections 1—1 previously constructed so that no nails or fastenings are required at the time of assembling the crate. Therefore, for the purpose of holding the

5 sections 11, 12, 13 and 14 in place to cooperate with the rigidly connected side sections, a suitable metallic tape T is wrapped about the outside of the crate sections. As shown in Figure 1 the said tape T is wrapped transversely about the crate three times, and vertically about the same twice, and in each instance the ends of the tape being fastened by a conventional and well known metallic form of tie or coupling T' used in the application of said tape to crates and the like.

Thus it will be apparent that the metallic tapes T securely hold the relatively removable sections of the crate in place. And, when all of the sections are assembled to 20 form the complete crate it will be apparent that since the two side units or sections extend beyond the limits of the cabinet at the bottom and top thereof, these members will receive substantially all of the blows that 25 come to the crate and these blows are then transmitted by the fastening bolts 4 to the sides of the cabinets. As this shearing force thus applied is distributed to the sides of the cabinet no harm can result, because the 30 cabinet has great strength against shearing forces which are applied in any direction within the plane of the sides. Also the projection of the side sections beyond the limits of the side of the cabinet serve to protect 35 the top, bottom, front and back of the cabinet against blows that may be produced at right angles thereto. To further assist in the complete protection of the cabinet or other article within the crate the same may 40 be encased or enveloped by a sheet of heavy wrapping paper, cardboard or equivalent material M which will prevent surface scratching and also act as a weather-proof protection.

45 Without further description it is thought that the features and advantages of the invention will be readily apparent to those skilled in the art and it will of course be understood that changes in the form, proportions and minor details of construction 50 may be resorted to without departing from the spirit of the invention or scope of the appended claims.

I claim:

55 1. A crate of the class described comprising a plurality of separate crate frames arranged for assembling about the article to be shipped, binders for holding the said frames in assembled relation, and fasteners 60 connecting a frame and the article.

2. A crate of the class described comprising a plurality of separate crate sections for assembling in box form about the article to be shipped, said sections being side, top, bottom and end sections, binders for securing

together all of the said sections, and fastening devices fitted to the article and having a fastening connection with certain of the frame sections.

3. A crate of the class described, including 70 in combination with the article to be shipped, a crate section adapted to be rigidly connected to the article, other crate sections adapted to be assembled about the article, and a binder engaging the crate section carried by the article and also said other crate sections for holding the same in assembled relation about the article to be shipped. 75

4. A crate of the class described, including 80 in combination with the article to be shipped, a crate section rigidly connected to the article and projecting beyond the same, other crate sections loosely assembled about the article and cooperating with the article carried section to form the complete crate, 85 and binders for holding the said other sections in place about the article.

5. A crate of the class described, including 90 in combination with the article to be shipped, a pair of crate sections having portions extending beyond the limits of the article to be shipped, means for rigidly connecting said sections to the article, other crate sections arranged about the article and interfitting with said first mentioned sections, and binder tapes passed around all of 95 said crate sections.

6. A shipping crate of the class described, including 100 in combination with the article to be shipped, a pair of side sections of greater dimensions than the article to be shipped, means for rigidly connecting said crate sections to the article and a plurality of other crate sections interfitting with the projecting portions of said first mentioned crate sections and arranged loosely about the remainder of the article, and a plurality of flexible binder tapes embracing all of said sections. 105

7. A shipping crate of the class described, including 110 a thrust receiving section adapted to be rigidly connected to the article to be shipped, and other crate sections assembled about the said article and cooperating with the thrust section to provide a complete crate, and means for holding all of said sections in assembled relation. 115

8. A shipping crate of the class described, including 120 in combination with the article to be shipped, having openings therein, of a crate section having openings corresponding to the openings in the article to be shipped, fastening devices for clamping the sections and the article together at the locations of said openings, other crate sections assembled about the article to be shipped and means 125 for holding the latter in position.

9. A shipping crate of the class described, including 130 in combination with the article to be shipped, of a pair of crate sections adapted to be arranged at opposite sides of the ar-

4

ticle, means for rigidly securing said sections to the article, other crate sections adapted to be disposed at right angles to said first mentioned crate sections and protecting the ends, top and bottom of said article, and binding tapes for holding said latter crate sections in position.

10. A shipping crate of the class described, including in combination with the article to be shipped, a pair of main crate sections, means for rigidly securing said main crate sections to the article to be shipped, top and bottom sections loosely fitting between the projecting end portions of said main sections, end sections fitting between the projecting end portions of the top and bottom sections and binding tapes passing about all of the crate sections at right angles to hold the relatively loosely interfitting sections to the main sections and to the article to be shipped.

11. A shipping crate including, in combination with the article to be shipped, a main crate section having projecting impact receiving end portions, and means for forming a rigid connection with the article thereby to distribute compressive shearing and tensioning strains from the section directly to the article.

30. 12. A shipping crate including a plurality of sections forming a hollow parallelogram, means for connecting certain of said sections directly to the article to become in effect an integral part thereof, and other means for holding the remaining sections in place.

13. A shipping crate of the class described, including in combination with the article to be shipped, a pair of outside crate sections having impact receiving edge portions projecting beyond the limits of the article to be shipped, means for rigidly connecting said sections to the article, and other crate sections filling the space between the projecting end portions.

40. 14. In a shipping crate, a fastening device for securing the crate to the article contained therein, said device consisting of a member having washer elements thereon for engaging with opposite sides of a wall of the article within the crate, and said member projecting through an opening in the crate to receive a tensioning nut and clamping washer, thereby to rigidly clamp the article within the crate thereto.

45. 15. In a shipping crate, a fastening device for securing the crate to the article contained therein, said device consisting of a bolt having thereon spaced washers for engaging with opposite sides of a wall of an article within the crate, and one of said washers having means for embedding itself in the crate, and a tensioning nut and bearing washer adapted to be applied to the portion of the bolt projecting beyond the crate.

50. In testimony whereof I hereunto affix my signature in the presence of two witnesses.

FRED A. SCHMITZ.
